UNITED STATES PATENT OFFICE.

HENRY STEARNS, SAM WILSON, AND ERNEST B. WHINNERAH, OF
MANCHESTER, ENGLAND.

ACETYLENE-GAS-GENERATING LAMP.

SPECIFICATION forming part of Letters Patent No. 629,309, dated July 18, 1899.

Application filed March 27, 1899. Serial No. 710,733. (No model.)

To all whom it may concern:

Be it known that we, HENRY STEARNS, cycle-manufacturer, of 68 Wilmslow road, Rusholme, SAM WILSON, plumber, of 119 Wilmslow road, Rusholme, and ERNEST B. WHINNERAH, builder, of 10 Brook street, Fallowfield, Manchester, in the county of Lancaster, England, subjects of the Queen of Great Britain, have invented a new and useful Improvement in and Relating to Acetylene-Gas Lamps for Cycles or other Analogous Uses, of which the following is a specification.

Our invention relates to improvements in and relating to acetylene-gas lamps for cycles, carriages, or other analogous uses.

The objects of our invention are, first, to provide a lamp in which the water may be allowed to pass in regular or defined quantities to the carbid-chamber, by which means gas may be regularly generated and a regular emission thereof at the burner, (thus when the gas is ignited a steady light may be produced at the burner;) secondly, to provide an arrangement in connection with the burner whereby the thoroughfare may always be maintained open, so as to allow of the free exit of gas as generated.

It is well known that in acetylene-gas lamps as now generally used the water is allowed to pass to the carbid or chemical chamber in irregular quantities, whereby gas is irregularly generated, consequently affecting the light or flame at the burner where the gas is ignited; also, when the gas is turned off or the light is turned out a deposit of hard matter is formed at the burner which obstructs the passage. A pricker or instrument is usually employed for the purpose of removing the deposit. This operation is often difficult and tedious, having to be performed under difficult circumstances, such as trimming the burner during the darkness of night.

In order that our invention may be clearly comprehended, we have hereunto annexed a sheet of drawings illustrating our invention, like letters of reference indicating like parts.

Figure 1 is an elevation of a cycle-lamp, part in section in order to show the application of our invention thereto. Fig. 2 is a plan showing the upper part of Fig. 1—that is, the pinion and spindle in the water-chamber.

According to our invention we employ in the water-chamber *a* a spindle *b*, which passes through a tube or thoroughfare *c*, situate at the lower part of the water-chamber *a*, and into or terminates within the carbid or chemical chamber *d*, the construction or arrangement of which chambers *a* and *d* are well known. On the spindle *b* we provide a conically-shaped piece *e*, which is situate at the mouth or entrance of the thoroughfare *c*. The said spindle *b* is also provided at its upper part with a toothed piece or rack *f*, which is held in position by means of a fixed guide-piece *g*, fixed at the inside of the water-chamber. (See Fig. 2.) The said rack-piece *f* engages with a correspondingly-toothed pinion-wheel *h*, which is supported by a spindle *i*, provided with a knob or turning-piece *j*. We provide the knob with a stop-piece *v*. We also provide a stop-piece *v'* at the side of chamber *a*, so that when *j* is turned *v* may come in contact with *v'* and limit rotation of *h*; consequently the left of valve *e*.

Within the hollow stem *k* we employ a wire piece or "pricker" *o*, which passes through the thoroughfare of the stem to or near the outer upper extremity of the burner *l* and is suitably connected at its other end to a screw-threaded piece *s* by means of a connecting piece or spindle *t*, which piece *t* when the screw *s* is suitably turned travels toward the stem *k* and covers or closes the entrance of the thoroughfare in the stem and situate within the carbid-chamber. When this operation occurs, the wire piece *o* is consequently pushed forward and the end *o'* is caused to pass through or out of the burner, and accordingly as the screw-threaded piece *s* is turned in direction to the right or to the left hand the wire *o* may be pushed through or withdrawn from the burner *l*. Thus any deposit which may be situate over the orifice at the outside of the burner may be removed, and a free admission of gas is allowed to pass through the same, the removal of which is an important object to be attained by this our invention.

When the spindle *b* is actuated or the conical piece *e* raised, as shown in dotted lines, Fig. 1, so as to admit water to the chamber *d*, the conical form of the piece *e* allows more or less in quantity to pass through the thor-

oughfare *c*, according to the section of the said piece *e* which may be presented to the entrance to the said thoroughfare. The water may then pass by gravity down the spindle *b* and pass off at its extremity to or come in contact with the chemical compound in the chamber *d*. The stop-pieces *v* and *v'* prevent the piece *e* from being lifted too high from its seat at entrance to tube *c*, so as to allow only defined quantities of water to pass to chamber *d*.

We claim as our invention—

1. In an acetylene-gas lamp, the combination with the water and carbid chambers having a communicating passage between them, of a valve for closing said passage, a rack carried by the valve and located within the water-chamber, a pinion meshing with said rack, also located within the water-chamber, means arranged at one side of the lamp-body for rotating the pinion to cause the rack and valve to move up and down for the purpose specified, and a wire or spindle secured to the under side of the valve and depending into the carbid-chamber for conducting the water thereinto.

2. In an acetylene-gas lamp, the combination with the water and carbid chambers having a communicating passage between them, of a conical valve for closing said passage, a rack carried by the valve, a pinion meshing with said rack, for raising and lowering the same for the purpose specified, a thumb-but-

ton located outside the lamp-body and secured to the pinion for operating the same, means for locking said button in different positions to control the seating of the valve, and a spindle secured to the apex of the valve and depending into the carbid-chamber for conducting the water thereinto, substantially as described.

3. In an acetylene-gas lamp, the combination with the water and carbid chambers one located directly above the other and having a tubular connection between them, a conical valve for closing said tubular connection, a rack carried by the valve and located within the water-chamber, a guide for said rack, a pinion meshing with said rack also located within the water-chamber, a button located at one side of the lamp and having a connection with the pinion for rotating the same, means for locking said button in different positions to control the seating of the valve, and a spindle secured to the apex of the valve and depending into the carbid-chamber for conducting the water thereinto, substantially as described.

Dated this 23d day of January, 1899.

HENRY STEARNS.

SAM WILSON.

ERNEST B. WHINNERAIL.
